Attorney

UNITED STATES PATENT OFFICE

FREDERICK F. PALMORE, OF EL RENO, OKLAHOMA, ASSIGNOR OF ONE-HALF TO DAVID C. ROBERTS, JR., OF RUSH SPRINGS, OKLAHOMA

KEY RING HOOK

Application filed July 30, 1931. Serial No. 554,139.

This invention relates to key ring hooks, and more particularly to a device of this kind which may be readily mounted on a belt or other support.

5 An object of this invention is to provide a device of this kind which is so constructed that the key ring may be readily mounted on the device and when mounted thereupon, will not become lost.

10 Another object of this invention is to provide a novel locking means for locking the key ring on the device and maintaining the key ring in the desired position on the body of the wearer.

15 A further object of this invention is to provide resilient means for resiliently securing the device to a belt or other flat support, this resilient means limiting the movement of the key ring on the device.

20 The above and various other objects and advantages of this invention will in part be described in and in part be understood from the following detailed description of the present preferred embodiment, the same being illustrated in the accompanying drawings, wherein:—

Figure 1 is a detail front elevation of a device constructed according to the preferred embodiment of this invention in applied position;

30 Figure 2 is a detail side elevation of the device partly in section showing the method of inserting the belt within the holder;

Figure 3 is a detail side elevation partly 35 in section showing the method of inserting the key ring within the device after the belt has been mounted therein, and

Figure 4 is a detail side elevation partly 40 in section showing both the belt and the key ring mounted within the holder.

Referring to the drawings wherein like numerals of reference designate corresponding parts throughout the several views, the numeral 10 designates generally a flat belt or 45 support of desired width which may be worn

by an individual, and the numeral 11 designates an elongated flat plate having one end 13 thereof free, this free end being disposed downwardly. The upper end 12 of the plate 11 is bent in looped form and continued 50 downwardly, as at 14, in parallel relation to the plate 11, which extension 14 is provided with a U-shaped key ring supporting member 15 having a free end 16 engaging against the outer face of the plate 11 and disposed 55 upwardly from the free end 13 of the rear plate 11. This U-shaped member 15 is adapted to removably receive a key ring 17 and support this key ring in desired location on the belt 10.

60 A second plate 18 is disposed inwardly of the outer extension 14 and is provided with a U-shaped upper end portion 19 which has the free leg thereof secured to the upper end of the rear or inner plate 11 by means of a rivet 20 or the like. This inner plate 18 closely engages against the inner face of the extension 14 and the U-shaped upper portion 19 follows the configuration of the looped portion 12. The lower end of this plate 18 has 65 an extension 21 disposed between the outer plate 14 and the inner plate 11 and this extension 21 is positioned upwardly of the free end 16 of the U-shaped member 15.

70 The inner end of this extension 21 resiliently engages against the outer face of the inner plate member 11 and acts to limit the upward movement of the key ring 17 not only during the mounting of the key ring on the ring supporting member 15 but also during the time that the device is positioned on the belt 10.

75 In the use of this device, the key ring 17 may be mounted on the ring supporting member 15 by disposing the ring between the lower end 13 of the inner plate 11 and the outer surface of the ring supporting member 15 adjacent the lower end 13 of the inner plate 11. The ring 17 may be moved upwardly between the free leg 16 and the lower 80 85 90

- end portion 13, thereby forcing the outer plate 11 outwardly until the the ring 17 passes the upper end of the inner leg 16 whereupon the inherent resiliency of the outer plate 14 will spring the ring supporting member 15 inwardly toward the inner plate 11, thereby locking the ring 17 on the ring supporting member 15. During the mounting of the ring 17 on the supporting member 15, the belt engaging member 18 will remain into engagement with the belt 10, this belt engaging member 18 being free of the outer plate 14. As the ring 17 is moved upwardly between the plate 11 and the inner surface of the leg 16, the stop member 21 will limit the upward movement of the ring 17 so that it will be retained within the ring supporting member 15 after it has passed the upper end of the inner leg 16.
- 20 In order to mount the belt 10 on the device, this belt 10 may be passed through the loop formed by the inner plate 11 and the plate member 16 or the belt may be inserted between the inner plate 11 and the lower portion 25 of the ring supporting member 15 and moved upwardly, the plate member 18 with the stop member 21 being also forced outwardly so as to provide a passage for sliding the belt upwardly until the lower edge 30 of the belt 10 has passed the stop member 21, whereupon this plate member 18 will spring inwardly so that the inner end of the stop member 21 will resiliently engage the outer surface of the inner plate 11.
- 35 It will be obvious, from the foregoing, that when the key ring 17 has once been mounted on the device herein disclosed, it will be firmly locked and will be retained within the ring supporting member 15, due to the inherent resiliency of this plate 14 in constantly maintaining the ring supporting member 15 into engagement with the inner or body plate member 11.
- 40 It is, of course, understood that various changes and modifications may be made in the details of construction and design of the above specifically described embodiment of this invention without departing from the spirit thereof, such changes and modifications being restricted only by the scope of the following claim.
- 45 I claim:—
- 50 A key ring holder of the character described comprising an inner plate, an outer plate formed with said inner plate and disposed in spaced relation thereto, a U-shaped ring supporting member formed with one end of said outer plate and having one leg thereof resiliently engaging the outer face 55 of said inner plate, and an L-shaped belt engaging member disposed between said inner and said outer plates and having one leg thereof extending transversely of said inner and said outer plates, the opposite leg of 60 said L-shaped member being looped at the

upper end and engaging the inner face of said outer plate, outward movement of said L-shaped member coactively moving said U-shaped member outwardly to permit insertion of a belt by upward movement along 70 said inner plate, said transverse leg extending between said plates inwardly of said ring supporting member and cooperating with said ring supporting member in releasably locking a ring thereupon.

75 In testimony whereof I hereunto affix my signature.

FREDERICK F. PALMORE.
